UNITED STATES PATENT OFFICE

HUBERT T. FOOTE, OF NEW YORK, N. Y.

ATTACHMENT FOR GAS-BURNERS.

SPECIFICATION forming part of Letters Patent No. 361,818, dated April 26, 1887.

Application filed January 7, 1887. Serial No. 223,640. (No model.)

To all whom it may concern:

Be it known that I, HUBERT T. FOOTE, of the city, county, and State of New York, have invented a new and Improved Heating Attachment for Gas-Burners, of which the following is a specification.

The attachment is adapted for heating irons used in curling, crimping, or fluting. It may also heat irons for molding, stamping, and various other purposes. It is arranged to mingle the air and the gas, after the fashion known as the "Bunsen" burner, so as thereby to produce a flame with great heat and without smoke, and it is equipped with arms adapted to hold an iron in position to be heated with the handle depressed and kept cool. It is equipped to receive a peculiarly-fitted piece, which, engaging strongly therewith, may hold a vessel over the flame for heating water or other fluid.

The interior is specially adapted to match on ordinary gas-burners and be firmly supported thereby without danger of injuring the burner or the tip, even in case a detachable lava tip is employed.

The main body may be made of malleable cast-iron, with the several arms formed in one therewith; but I prefer that the arms at the top be made separately of elastic metal and attached.

The accompanying drawings form a part of this specification, and represent what I consider the best means of carrying out the invention.

Figure 1 is a side elevation of the burner with a curling-iron in position to be heated. Fig. 2 is a corresponding view from the right in Fig. 1. Fig. 3 is a top view with the irons removed. Fig. 4 is a horizontal section on the line $x-x$ in Fig. 1. Fig. 5 is a perspective view of a frame for supporting articles to be heated. Figs. 6, 7, and 8 are vertical sections with certain portions removed, showing the application to different styles of gas-burners. Fig. 9 shows the application to an alcohol or other lamp.

Similar letters of reference indicate corresponding parts in all the figures where they occur.

Δ is a ring, and A' are radial arms extending outward and also upward therefrom. These arms join A to the interior of a hollow conical

casing, B , which is provided near the base with an arm, B' , and near the top with two arms, B^2 B^3 . These latter lie on the same side of the cone as the arm B' and stand nearly parallel to each other. When a curling-iron, D , is applied in the position indicated in Fig. 1, it is engaged between the arms B^2 B^3 and rests astride of the arm B' . The ring A is provided with three internal projections, a , by the aid of which it rests securely on the slight shoulder formed in the gas-burner M . The bearing afforded by these internal projections and the inner faces of the arms A' insures that the device will be firmly supported on a gas-burner of any of the ordinary forms.

The form of the interior is adapted to match on all ordinary forms of gas-burners. The old-fashioned iron burner, with slender body and a large base, will serve almost equally well. Figs. 7 and 8 show the device fitted on the two principal modifications of burners.

I have in my experiments made the conical casing B about two inches in height and one and a quarter inches in diameter at the bottom and a half-inch in diameter at the top; but these may be varied. It is important that the size of the whole apparatus and of the spaces for receiving air at the base of the device be adapted to mingle the air with the gas issuing from the top of the burner in the correct proportions for perfect combustion without any large excess of air. The flame issuing should fill the small orifice at the top of the cone with a strong blue flame sufficient to bathe the effective portion of an ordinary iron, D , presented thereto in the position shown.

On the exterior of the cone are shallow projections B^4 , in each of which is a hole, b^4 , adapted to receive and support one of the wires E' , extending downward from the ring E . These wires E' are bent, as shown, so that after they are sunk into these holes to a certain depth they are securely supported. These supports E' , thus formed and arranged, are able to reach down past the arms B^2 B^3 and engage in these holes b^4 , and thereby support the ring E . On this latter may rest a vessel for heating any liquid required in sickness or health.

When the iron D is hinged like ordinary curling-irons, the parts diverging below the hinge sit astride of a single bar, B' , and with

the aid of the arms B^2 B^3 above support the iron firmly. When a single iron for stamping or the like is to be heated, it may usually be supported by placing it in the proper position, 5 the arms yielding sufficiently by their elastic action to allow the application and exerting sufficient resilience to their elasticity to hold it firmly. When the apparatus is made with an especial view to heating single irons, there 10 may be two arms in place of the arm B' .

I have shown the arms B^2 B^3 as made from a separate piece of hard brass, or of hard iron or steel, with their ends rounded and slightly flared. These two arms are formed in a single 15 piece and are sprung into position partially embraced by lugs B^3 in the position shown. I prefer that these arms be constructed and attached in this way as giving a high degree of elasticity; but I believe the device will serve 20 well with the arms B^2 B^3 as well as the arm B' cast in one with B .

I have in my experiments made the ring A and the arms A' as a single casting of grey iron and cast the part B , with its attached 25 arms thereon, at a subsequent operation. To effect this the ends of the arms A' should be made clean by filing or otherwise, and the casting A A' is embedded in the properly-tempered earth to form a core. This core is put in the mold 30 in the proper position to form a hollow interior of the casing B . The metal for the latter, being poured at a good heat, attaches itself to the ends of the previously cold arms A' in a method sometimes known as "burning," and 35 the device works as a single casting. It may be practicable to make the whole in a single casting by sufficiently skillful coring.

Although I have described this device as an attachment for gas-burners, and intended 40 mainly for use as such, I believe it practicable to utilize the principle and realize a large portion of the advantages by providing arms corresponding to B' B^2 B^3 on the exterior of a suitable alcohol-lamp. In such case there 45 need be no provision for mingling air with the flame within a casing analogous to B , but the exterior of the lamp will correspond to B . There will be equal need of the holes b^4 to receive the wires E' from the ring E .

50 It is important that the lamp, when thus equipped and used, be held firmly, so that the application and removal of an iron may be effected by one hand, even if it requires considerable force. To do this I provide the lamp 55 with an arm adapted to match under the edge of a table or shelf on which it may be placed and a clamping-screw with a shoe to take firm hold of such support. Fig. 9 shows a lamp thus equipped.

G is a portion of the table.

60 H is a stout arm extending from the body of the lamp under the edge of the table and carrying a stout thumb-screw, I, acting against the table through the medium of a shoe, J. By this means the lamp may be firmly set. A 65 portable gas-burner supplied by a hose may be similarly held. As the position on the edge of the table allows the handle of the iron to extend down to any distance required, the device may be worked in the same manner as 70 with the gas-burner.

I attach much importance to the fact that my device holds the iron in the inclined position represented, so that a small flame can bathe a large portion or the whole of the part 75 to be heated, and that the handle or handles are extended downward out of the influence of the flame. I also attach importance to the fact that the device, when used with gas, mixes the air and gas so as to make a non-luminous 80 and non-smoking but highly-heating flame without involving complication or expense. The whole may be sold at a low price. The main portion B , with its permanent attachments, give promise of enduring ordinary usage 85 for a long period. The removable device E E' may be renewed at intervals, if desired.

I can use with some success arms B^2 B^3 , which are without elasticity.

I claim as my invention—

1. The casing B , in combination with provisions for producing a flame at the top, and with the arms B' B^2 B^3 , adapted for holding an iron in an inclined position in the flame, substantially as and for the purposes herein specified. 90

2. The heating-case B and internal ring, A , and arms A' , adapted to apply on ordinary gas-burners and to make the proper mingling of air and gas for perfect combustion, in combination with each other and with the arms B' B^2 B^3 , for holding an iron thereon, substantially as herein specified. 95

3. The casing B , having the arms B^2 B^3 to aid in holding an iron, D , in combination with the detachable ring E , having arms E' , adapted 100 to engage it with B , so as to enable the device to serve exchangeably for heating irons and for heating liquids at will, as herein specified. 105

In testimony whereof I have hereunto set my hand, at New York city, New York, this 110 4th day of January, 1887, in the presence of two subscribing witnesses.

HUBERT T. FOOTE.
